DESIGN FOR A PERCOLATOR OR THE LIKE

Peter Muller-Munk, Pittsburgh, Pa., assignor to
The Hartford Products Corporation, Chicago,
Ill., a corporation of Connecticut

Application October 30, 1946, Serial No. 134,379

Term of patent 14 years

(Cl. D44—26)

To all whom it may concern:

Be it known that I, Peter Muller-Munk, a citizen of the United States, residing at Pittsburgh, in the county of Allegheny and State of Pennsylvania, have invented a new, original, and ornamental Design for a Percolator or the like, of which the following is a specification, reference being had to the accompanying drawing, forming part thereof.

Fig. 1 is a plan view of a percolator, embodying my new design.

Fig. 2 is an elevational side view thereof.

I claim:

The ornamental design for a percolator or the like, substantially as shown.

PETER MULLER-MUNK.
